Inventor

A. Johnson.

By *Alfred Johnson*, Attorney

UNITED STATES PATENT OFFICE.

AUGUST JOHNSON, OF PORTLAND, OREGON.

GRATE-BAR

1,401,783.

Specification of Letters Patent. Patented Dec. 27, 1921.

Application filed October 17, 1919. Serial No. 331,357.

To all whom it may concern:

Be it known that I, AUGUST JOHNSON, a citizen of the United States, residing at Portland, in the county of Multnomah and 5 State of Oregon, have invented certain new and useful Improvements in Grate-Bars; and I do hereby declare the following to be a full, clear, and exact description of the invention, such as will enable others skilled 10 in the art to which it appertains to make and use the same.

This invention relates to new and useful improvements in grate bars especially adapted for furnaces in which is burnt sawdust, wood shavings, slab wood and mill 15 refuse and has for one of its objects the provision of a device of this character, which is light in weight so that the same can be readily handled, and one which will not 20 readily warp or buckle from intense heat which is frequent when burning fuel of the above stated character.

Another object of this invention is the provision of means which will efficiently 25 support the bar and prevent or obviate any danger of the bar falling when being cleaned of clinkers, and is also so constructed that the tools used in cleaning will not catch or strike against the end of the 30 bar, further insuring against the danger of unseating the bar during cleaning processes.

A further object of this invention is the provision of a grate bar of the above stated character, which shall be simple, durable, and 35 efficient, and which may be manufactured and sold at a comparatively low cost.

With these and other objects in view as will become more apparent as the description proceeds, the invention consists in certain 40 novel features of construction, combination, and arrangement of parts as will be hereinafter more fully described and claimed.

For a complete understanding of my invention, reference is to be had to the following description and accompanying drawing, in which:—

Figure 1 is a plan view of a grate bar constructed in accordance with my invention,

Fig. 2 is a longitudinal sectional view of the same,

Fig. 3 is a transverse sectional view taken on the line 3—3 of Fig. 1,

Fig. 4 is a side elevation partly in section illustrating a plurality of grate bars

arranged within a fragmentary portion of the furnace.

Referring in detail to the drawing, the numeral 1 indicates as an entirety a grate 60 bar consisting of parallel ribs 2 that increase in depth toward the centers thereof. These are preferably four in number and are cast integrally with connecting elements 3. The connecting elements 3 are arranged 65 adjacent each end and at a point intermediate the ends, and terminate short of the lower edge of the ribs. The top faces of the elements 3 are flush with the top faces of the ribs 2 to provide a substantially 70 smooth or even top surface to the grate bar. Spacing lugs 4 are formed upon the outer ribs 2 in alignment with the connecting elements 3 and are of substantially the same shape and outline as the connecting 75 ribs 3.

The top faces at the ends of the ribs 2 are inclined as shown at 5 so as to prevent cleaning tools from catching on the ends of the ribs when cleaning the grate bar of 80 ashes. The ribs 2 decrease in thickness from their upper faces toward their lower faces so as to decrease the amount of material used in constructing the bar thus making the same of a lighter weight. The connecting elements 3 also decrease in thickness from their upper ends toward their lower ends, further decreasing the weight of the 85 bar and therefore it will be seen that the bar when constructed in accordance with 90 the foregoing will be comparatively light in weight so that the same can be readily and conveniently handled when being removed or replaced in a furnace, also reducing the cost of manufacture of the de- 95 vice.

One of the ends of each of the ribs 2 in its lower edge is provided with a notch 6 for the purpose of engaging or receiving a bearing or support 7 in a furnace 8. Each 100 notch 6 is provided with a straight side wall 9 and a straight top wall 10 and an inclined side wall 11. The bearings 7 are provided with inclined faces 12 to conform to the walls of the notches 10 so that the 105 grate bar is efficiently supported and locked in place against longitudinal movement within the furnace 8 thereby obviating the danger of the grate bar falling when clinkers are being removed therefrom.

While I have shown and described the preferred embodiment of my invention, it

will be understood that minor changes in construction, combination, and arrangement of parts may be made without departing from the spirit and scope of the invention as claimed.

Having thus described my invention, what I claim is:—

A grate structure having bars spaced apart at adjacent ends and with said ends chamfered for the purpose specified, supporting means for said bars adjacent said ends having a passageway therethrough in communication with the space intermediate the ends and with the ashpit, said bars each having a recess with a substantially straight side wall and the opposite side wall de-

flected relatively thereto so that the recesses will be widest at the entrance, said support having a projection on each side of the passageway to enter the recesses and conforming substantially to the shape of the recesses, and said bars having lateral ribs terminating relatively close to said projections whereby ashes will not accumulate on the supporting member but will be directed through the passageway. 20 25

In testimony whereof I affix my signature in presence of two witnesses.

AUGUST JOHNSON.
